(57) CLAIM

The ornamental design for a undergarment as shown and described.

DESCRIPTION

FIG. 1 is a perspective view of an undergarment of our new design;

FIG. 2 is a left side view of the undergarment shown in FIG. 1;

FIG. 3 is a right side view of the undergarment shown in FIG. 1;

FIG. 4 is a front view of the undergarment shown in FIG. 1;

FIG. 5 is a rear view of the undergarment shown in FIG. 1;

FIG. 6 is a top view of the undergarment shown in FIG. 1; and,

FIG. 7 is a bottom view of the undergarment shown in FIG. 1.

The broken lines in the drawings show portions of the undergarment for illustrative purposes only and form no part of the claimed design.

1 Claim, 7 Drawing Sheets
